UNITED STATES PATENT OFFICE.

ALBERT WELLS BUEL, OF NEW YORK, N. Y., ASSIGNOR OF ONE-HALF TO
DAVID LEAVITT HOUGH, OF SAME PLACE.

DESIGN FOR A CHANNEL-BAR FOR TUNNEL OR SIMILAR CASINGS.

SPECIFICATION forming part of Design No. 28,952, dated June 28, 1898.

Application filed April 14, 1898. Serial No. 677,630. Term of patent 14 years.

To all whom it may concern:

Be it known that I, ALBERT WELLS BUEL, a citizen of the United States, residing in the borough of Manhattan, in the city of New York, in the county of New York and State of New York, have invented and produced a new and original Design for Channel-Bars for Tunnel-Casings, of which the following is a specification, reference being had to the accompanying drawings, forming part thereof.

Figure 1 is a perspective view of a channel-bar for tunnel-casings, showing my new design. Fig. 2 is a side view of the same. Fig. 3 is a transverse sectional view.

As shown in the drawings, the leading or material feature of my design consists of the rib *a*, arranged at one edge of the web or body *b* at the side opposite from two projecting edge wings *c* and *c'*, respectively, and forming a continuation or extension of one of said edge wings *c*. The rib *a* projects at right angles to the web *b* and extends longitudinally with relation to the same. The wings *c* and *c'* project at right angles to the web *b* at the side opposite from the rib *a* and extend longitudinally at the respective edges of the web. The outer face *d* of the rib *a* is flat, while its inner face *d'* is curved or rounded toward its outer end. The outer face *e* of the wing *c* and the outer face *f* of the wing *c'*,

respectively, are likewise flat, while the inner faces *e'* and *f'*, respectively, of said wings are likewise curved or rounded toward their outer ends, as shown. The flat face *d* of the rib *a* and the flat face *e* of the wing *c*, respectively, thus conjointly form a continuous flat face at the side of the channel-bar opposite from the wing *c'*. The rib *a* projects in a direct plane corresponding to the plane of the wing *c*, and said rib is shorter than the wing *c* in its projection or extension beyond the web *b*. The web extends in a continuous straight transverse plane between the rib *a* and the wing *c* and the opposite wing *c'*. One of the wings *c* is shown longer than the other wing.

The channel-bar, including the web and the wings and rib, is segmentally curved, as shown.

Having described my invention, what I claim as new, and desire to secure by Letters Patent, is—

The design for a channel-bar for tunnel and similar casings, substantially as herein shown and described.

In testimony whereof I have hereunto set my hand, in presence of two witnesses, this 10th day of March, 1898.

ALBERT WELLS BUEL.
